UNITED STATES PATENT OFFICE

DALE T. SANDERSON, OF BURWYN, ILLINOIS, ASSIGNOR TO WILLIAMSON CANDY COMPANY, OF CHICAGO, ILLINOIS, A CORPORATION OF ILLINOIS

DISPENSING CONTAINER FOR PIECE GOODS

Application filed February 27, 1928. Serial No. 257,523.

This invention relates to dispensing containers and relates particularly to containers for piece goods.

The object of the invention is to provide a dispensing container for the purpose specified comprising means for conspicuously displaying a piece of goods packed in said box, when the box is opened to expose the contents thereof, said display means preferably being constructed and arranged to provide an advertising medium for the goods so displayed.

Stated broadly, containers embodying my invention and improvements comprises a display flap of flexible sheet material, an edge of which is attached to a wall of the container, said flap being provided with lines of fold adapted to form a ledge for supporting a piece of goods packed in said container, and means for securing a piece of goods in position on said supporting ledge, the relation being such that when said flap is folded down into a box the piece of goods supported thereon will be within the container and the flap will be disposed substantially flatwise there-in and being such, also, that when said flap is turned into extended position, the piece of goods secured thereto will be conspicuously exhibited.

Specifically, the means for securing a piece of goods to said flap, consists of a strap or band, opposite ends of which are attached to said flap in position to extend across the lines of fold which define the supporting ledge for the piece of goods secured thereto, whereby, when said flap is turned into extended position and is folded to form said supporting ledge, the distance between the attached ends of said bands will be reduced sufficiently to permit a piece of goods to be inserted between said band and the body portion of said display flap.

In what I now consider the preferable embodiment of the invention, said band is formed integral with said display flap by slitting it on lines to provide a band of desired length and shape.

In accordance with my invention, also, a dispensing container embodying my invention and improvements also comprises the various other features, combinations of fea-

tures and details of construction hereinafter described and claimed.

In the accompanying drawings in which my invention is fully illustrated,

Figure 1 is an isometric view of what I now consider a preferable form of dispensing container embodying my invention and improvements, shown with the cover thereof removed and the display flap turned into raised or extended position to exhibit a piece of goods packed in said container and secured thereto.

Figure 2 is a partial longitudinal sectional view of the container shown in Fig. 1, with the cover removed and the display flap in raised or extended position.

Figure 3 is a view similar to Fig. 2 showing the display flap folded down into the container.

Figure 4 is a fragmentary view of a container embodying my invention and improvements in modified form, the display flap being shown in raised or extended position, the view showing the side of the container to which the piece of goods is secured.

Figure 5 is a fragmentary isometric view illustrating still another modification.

Figure 6 is a sectional view on the line 6—6 of Fig. 5.

Figure 7 is a fragmentary isometric view illustrating a further modification; and

Figure 8 is a side view thereof, the container being shown in sectional elevation.

Describing the invention with particular reference to Figs. 1, 2 and 3, of the drawings, in the first instance, *a* designates the body portion of a dispensing container embodying my invention and improvements as a whole, which we will assume is made of cardboard or other suitable sheet material, said container being of box form. As used for packing and shipping goods, the top of the box will be closed by means of a suitable cover. Said cover, however, has no relation to the present invention and the same is not, therefore, shown.

As shown in the drawings, a plurality of separate pieces of articles 1 are shown packed in the container *a*. Said pieces 1 may exemplify many different kinds of goods, as, for

example, candy bars as put up for shipment and sale.

In accordance with my invention, a display flap a' of suitable sheet material, preferably flexible material, as cardboard, is secured to an end wall of the container a , simple means for this purpose consisting of staples 2.

In accordance with my invention, a piece of goods 1 packed in the container a , is secured to the side of the flap a' which, when said flap is folded downwardly into the container, as shown in Fig. 3, will be disposed on the underside of said flap, so that, when said flap is turned into raised or extended position as shown in Fig. 2, the piece of goods attached thereto will be conspicuously displayed.

Preferably, also, the flap a' will be proportioned to provide an unobstructed space 3 on the side thereof to which the piece of goods 1 is secured, adapted to receive an advertisement of the manufacturer of the goods packed in said container.

In accordance with my invention, the flap a' is scored transversely preferably adjacent to the edge thereof which it attached to the wall of the container a , to form lines of fold 4 and 5, adapted to define a ledge 6 on which the article 1 secured to said flap will rest.

What I now consider preferable means for securing the piece of goods in position on the supporting ledge of the flap a' consist of spaced bands or straps 7, opposite ends of which are attached to the flap a' at opposite sides of the lines of fold 4 and 5, so that said straps or bands 7 will extend across said lines of fold and preferably, also, so that the line of fold 4 adjacent the attached end of the flap will form the hinge of the flap.

The length of the straps or bands 7 is preferably substantially equal to the distance between the points of attachment of opposite ends thereof, respectively, to the flap a' , when said flap is in flatwise position, thus providing for disposing the body portion of the flap a' , beyond the line of fold 4, flatwise when said flap is folded downwardly into the container a , as shown in Fig. 3. Also, the supporting ledge 6 is made of such width—lengthwise of said flap—that when the flap a' is turned into partially raised or extended position and is subjected to endwise pressure beyond the outer ends of the straps or bands 7 to turn the same on the lines of fold 4 and 5 to form the supporting ledge 6, the distance between the attached ends of the straps or bands 7, respectively, will be reduced causing them to buckle sufficiently to permit a piece

of goods 1 to be inserted beneath said straps or bands resting upon the ledge 6. Also, after a piece of goods 1 has been inserted in position and the endwise pressure on the flap is relieved, the spring of the flap a' at the lines of fold 4 and 5 will cause said flap to

straighten at said folds to cause the straps or bands 7 to bind upon said piece of goods 1, thus securing it in position on the ledge 6. Obviously, with the construction and relation shown and described, a piece of goods 1 inserted beneath the straps or bands 7 and resting on the ledge 6 will form what may be referred to as a key which will limit turning movement of said flap a' in a direction to raise the same and will define its designed fully raised position, in which the piece of goods 1 secured thereto and any advertising matter on the side of said flap a' will be conspicuously displayed.

Instead of spaced bands 7 for securing the piece of goods 1 to the flap a' , my invention contemplates the use of a single relatively wide band positioned substantially at the transverse center of the flap a' and which preferably is relatively appreciably wider than the straps 7.

This modification is shown in Fig. 4 of the drawings, in which 7' designates a single, relatively wide strap or band for securing the piece of goods in position on the ledge on the display flap a' . All parts of the container other than said strap or band 7' are as near as may be identical in construction with corresponding parts shown in Figs. 1 to 3 of the drawings and are designated by the same reference characters.

As a still further modification of my invention, instead of the straps 7, Figs. 1, 2, 3, and 7', Fig. 4, for securing the piece of goods 1 in position on the ledge 6 defined by the lines of fold 4 and 5, I also contemplate see Figs. 5—6, the use of securing means consisting of a rubber band, opposite ends of which are attached to lugs 8, preferably formed by portions of the display flap a' which are stamped out therefrom around three sides, leaving said lugs attached to said flap at one end, as shown at 9, said lugs being provided at their free ends with enlargements 10, which provide shoulders 11 adapted for engagement by the loops formed by the ends of the rubber band, indicated at 12. Between the lugs 8, the rubber band 12 extends upwardly around the ends of the piece of goods rested on the ledge 6 and lengthwise over the same.

Other than the means for securing the piece of goods 1 to the display flap, consisting of the rubber band 12 and parts directly associated therewith, all parts of the container and display flap shown in said Figs. 5 and 6, are similar, as near as may be, with corresponding parts shown in Figs. 1 to 3, and are designated by the same reference numerals.

Still a further modification of my invention, as it relates to means for securing the piece of goods 1 to the flap a' , consists in dispensing with the line of fold 5 remote

from the attached end of said flap and which with the line of fold 4, which forms the hinge of the flap, defines the supporting ledge 6—thereby also eliminating said supporting ledge—the straps or bands 7 forming the only means for securing the piece of goods 1 to said flap.

This modification is shown in Figs. 7 and 8 of the drawings, in which 7² designates spaced straps, formed, as shown, by integral marginal portions of the outer end of the flap a', which is slit lengthwise to form straps of desired width and length. Said straps are folded on their lines of attachment to the flap a' and their inner ends are secured to the attached end of the flap a', the relation being such that said straps will extend across the single line of fold 4, which forms the hinge of said flap. With the described construction, it is obvious that when the flap a' is subjected to endwise pressure at a point beyond the outer ends of said straps and in the direction of the attached end of said flap, both the straps 7² and the flap will buckle 25 to provide a space between said straps and flap, said straps being proportioned to provide an opening large enough to receive a piece of goods 1, while, also, they will bind upon the piece of goods 1, when said flap is 30 turned into designed fully raised position, said piece of goods thus—as in the preferred form of the device—forming, in effect, a key, which in cooperation with the straps 7 will limit turning movement of said flap into 35 raised position.

Other than the parts shown in Figs. 7 and 8 which are herein specifically described and excepting also, that the line of fold 5 and thus the supporting ledge 6 are eliminated, 40 the parts of the container and display flap shown in Figs. 7 and 8, are substantially similar to corresponding parts shown in Figs. 1 to 3 and are designated by the same reference characters.

As in the case of the display flap a' shown in Figs. 1 to 3, the display flaps shown in Figs. 4 to 8 are preferably so proportioned as to provide unobstructed areas thereon adapted to receive advertisements.

I claim:

1. A container for piece goods comprising a display flap of suitable sheet material an edge of which is attached to a wall of the container, said flap being provided with a line of fold adjacent its attached edge adapted to form a hinge for said flap, and means for securing a piece of goods in position on said display flap, the relation being such that when said flap with the piece of goods secured thereto is folded down into the container said goods will be on the inner side thereof and within the container, and such also that when said flap is turned into raised position the piece of goods secured thereto will be displayed.

2. A container for piece goods comprising a display flap of suitable sheet material an edge of which is attached to a wall of the container, said flap being provided with lines of fold adjacent its attached edge adapted to form a ledge for supporting a piece of goods, and one thereof forming a hinge for said flap, and means for securing a piece of goods in position on said supporting ledge, the relation being such that when said flap with the piece of goods secured thereto is folded down into the container said goods will be on the inner side thereof and within the container, and such also that when said flap is turned into raised position the piece of goods secured thereto will be displayed.

3. A container for piece goods as specified in claim 1, in which when the flap with a piece of goods secured thereto, is turned into raised position, said piece of goods and the means for securing it to said flap will co-operate to define contemplated fully raised position of said flap.

4. A container for piece goods comprising a display flap of flexible sheet material, an edge of which is attached to a wall of the container, said flap being provided with a line of fold adapted to form a hinge therefor, and means for securing a piece of goods to said flap consisting of a strap opposite ends of which are attached to said flap in position to extend across the hinge thereof, whereby when said flap is subjected to endwise pressure applied beyond the outer end of said strap said flap and strap will buckle to permit a piece of goods to be inserted in position between said strap and flap.

5. A container for piece goods comprising a display flap of flexible sheet material, an edge of which is attached to a wall of the container, said flap being provided with a line of fold adapted to form a hinge therefor, and means for securing a piece of goods to said flap consisting of a plurality of bands opposite ends of which are attached to said flap in position to extend across the hinge thereof, whereby when said flap is subjected to endwise pressure applied beyond the outer end of said straps in the direction of the hinge of the flap, said flap and strap will buckle to permit a piece of goods to be inserted in position between said straps and flap.

6. A container for piece goods comprising a display flap of flexible sheet material, an edge of which is attached to a wall of the container, said flap being provided with a line of fold adapted to form a hinge therefor, and means for securing a piece of goods to said flap consisting of a strap formed integral with said display flap by slitting it on lines to provide a strap of desired length and shape, the relation being such

that said slits will extend across the hinge thereof.

7. A container for piece goods as specified in claim 4, in which the display flap is provided with two lines of fold which define a ledge for supporting a piece of goods packed in said container, and the strap for securing a piece of goods to said flap extends across both lines of fold.
- 10 8. A container for piece goods comprising a display flap of flexible sheet material, an edge of which is attached to a wall of the container, said flap being provided with a line of fold adapted to form a hinge therefor, and means for securing a piece of goods to said flap consisting of a strap opposite ends of which are attached to said flap in position to extend across the hinge thereof, whereby when said flap is subjected to end-
wise pressure applied beyond the outer end of said strap said flap and strap will buckle to permit a piece of goods to be inserted in position between said strap and flap and the relation being such that a piece of goods
25 secured to said flap by said strap will form a key and will limit turning movement of said flap to raise the same.

In witness that I claim the foregoing as my invention, I affix my signature this 21st
30 day of February, A. D. 1928.

DALE T. SANDERSON.
